UNITED STATES PATENT OFFICE.

ARCHIBALD BARR AND WILLIAM STROUD, OF GLASGOW, SCOTLAND, ASSIGNEES TO BARR AND STROUD, LIMITED, OF GLASGOW, SCOTLAND.

FIRE-CONTROL APPARATUS, DETERMINATION OF QUADRANT OF ENEMY'S COURSE.

Application filed September 6, 1923. Serial No. 661,309.

To all whom it may concern:

Be it known that we, ARCHIBALD BARR and WILLIAM STROUD, subjects of the King of Great Britain and Ireland, and both of Caxton Street, Anniesland, Glasgow, Scotland, have invented new and useful Improvements in Fire-Control Apparatus, Determination of Quadrant of Enemy's Course, of which the following is a specification.

10 The object of our invention is to determine, when an enemy ship is at or near the broad-side-on position whether the fore-and-aft line lies in the quadrants X Z or Y W (Figure 17 of the drawings to be referred to), where V T represents the line of sight, by which means (knowing which way the enemy is steaming) we can determine whether the component of the enemy's velocity along the line of sight is towards or 15 from our own ship or fort. We shall confine our attention in the first instance to the case of observations from a single ship.

15 In describing this invention reference will first be made to Figures 1, 2, 3, 4, 5, 6, 7, 8 and 17 of the drawings which are diagrams.

20 We install two instruments (hereinafter referred to as goniometers) capable of accurately measuring small angles in a horizontal plane, the one in a fore and the other in an aft position at as great a distance apart B as is practicable. The observers at the two goniometers are in telephonic (or other) communication with each other and they arrange to work upon two 25 definite points of the target, say, e. g., the bow and the stern, and to measure the horizontal angle subtended by these two points at the two goniometer stations A and C.

25 In Figure 1, A and C are the two stations and T represents the target, the angle of bearing α at C being represented by $\overline{TC}A$. Now it is clear that the goniometer angle as measured from C requires correction before it is compared with the goniometer angle as 30 measured from A because the distance CT is greater than AT . Drop a perpendicular from A on CT , viz., $\overline{AP}$; then $\overline{TA}$ is sensibly equal to $\overline{TP}$, remembering that T is usually at a very great distance R away; i. e. R is very great compared to B. If the

goniometer angle as measured from C is multiplied by the ratio

$$\frac{TC}{TP},$$

we get the value of the angle as though measured from P and this angle is strictly comparable with the angle as measured from A.

35 In Figure 2 we suppose that we are dealing with this multiplied angle at P and the actual goniometer angle at A. Let $T^1 T^2$ be the two points of the target with which we are dealing; then the measured goniometer angle at A is the angle $T^1 A T^2$ while the multiplied angle at P is $T^1 P T^2$. Let a perpendicular from the middle point of $T^1 T^2$ be drawn and suppose the line $T^1 T^2$ be oriented so that this perpendicular bisects PA at the point Q. Then it is clear that the angles $T^1 A T^2$ and $T^1 P T^2$ will be equal. The target is now exactly broadside on to the point Q. Suppose $T^1 T^2$ to turn through a very small angle in the direction of the arrow; then the perpendicular to $T^1 T^2$ will gradually approach A and recede from P while the angle subtended by $T^1 T^2$ at A will get larger and that at P will get smaller. Thus the criterion that the target is exactly broadside on (at all events to the point Q) is that the two angles shall be exactly equal.

40 If the target is in motion in the direction $T^1 T^2$ then, if the goniometer angle at A is greater than the angle at P, the target is moving away and vice versa.

45 If α represents the angle PCA , and R the range, we require mechanism for multiplying the goniometer angle measured at C by

$$\frac{TC}{TP},$$

i. e. by

$$\frac{R+B \cos \alpha}{R}$$

or by

$$1 + \frac{B}{R} \cos \alpha$$

50 and mechanism for comparing this angle with the goniometer angle at A.

One way of simply accomplishing the object in view is by means of a Wheatstone bridge circuit. Figure 3 shows such a circuit with supply wires + —, resistances c and a proportional to the goniometer angles measured at C and A respectively, the other resistances being as shown proportional to 1 and

$$10 \quad 1 + \frac{B}{R} \cos \alpha,$$

while G is the galvanometer. When the galvanometer is balanced we have

$$15 \quad \frac{c}{a} = \frac{1}{1 + \frac{B}{R} \cos \alpha}$$

or

$$20 \quad c(1 + \frac{B}{R} \cos \alpha) = a$$

or

the angle at P = angle at A

or target in broadside-on position.

25 Thus a deflection of the galvanometer pointer to one side of the zero, see Figure 17, will indicate one pair of quadrants Y and W, while a deflection to the other side will indicate the other pair X and Z.

30 As the goniometer angle at A is being measured, we have mechanism for varying proportionally the value of the resistance a , in the well known manner. The same remark applies to C and c , except that c may be conveniently situated in the region of C, in which case we may have low resistance cables to and from the station A or the resistance of these cables may be allowed for in the construction of the resistance c .

35 The adjustment of the arm of the bridge to the value

$$1 + \frac{B}{R} \cos \alpha$$

40 can be done in several ways. Since B is constant, it means shifting the contact by an amount proportional to

$$50 \quad \frac{\cos \alpha}{R}$$

This could be done (since there are two variables only) by a multiple cam such as is described in specification of United States Patent No. 1,460,221 or some simple mechanical device can be employed.

45 The accuracy will of course depend on the magnitude of B, $T^1 T^2$, and the smallness of R. In the case where the stations A and C are on land, the value of B can usually be made great. In order to increase the accuracy at sea by using a larger value of B we may use two goniometers as before but one on one ship and the second one on a sec-

ond ship. The electrical equipment will now be upon one of these ships and we must 65 possess means of measuring the value of B (the distance between the two goniometers) and the value of the angle T C A at the distant goniometer C. B may be measured in any well known manner. The Wheatstone 70 bridge circuit can now conveniently be arranged after the manner of Figure 4 where the arms are now c , a , R and $R + B \cos \alpha$. Having measured the value of B that value will be utilized for the determination of the 75 value of $B \cos \alpha$ by known methods, while the slider S is set to the known value of R.

80 Any convenient signalling method may be used for transmitting the reading of the distant goniometer. We may e. g. have the equivalent of a large clock-face associated with the mechanism which measures the distant angle and observe the "time" with a telescope at the near station and set off this "time" on a corresponding miniature clock-face associated with the mechanism for adjusting the value of c . The minute hand of the large clock may be replaced by a pointer moving through one revolution for ten seconds of angle, and the hour hand (if necessary) by a smaller pointer moving through one revolution for one hundred seconds of angle. We shall start at the near station by adjusting the value of c so that the galvanometer is roughly balanced and then adjust 95 the seconds accurately by means of the clocks.

90 A second method of carrying out our purpose is by means which may be shortly described as a mechanical equivalent of a 100 Wheatstone bridge system:—Suppose, see Figure 5, we set off R mechanically along the line O D and along the line D F simultaneously (say) and by means of a differential gear (or its equivalent) we add on a 105 part F E = $B \cos \alpha$; then if we have an arm O H pivoted at O and passing through E the angle E O D = θ is a measure of the ratio $R + B \cos \alpha : R$. Similarly, see Figure 6, if we set off O¹ D¹ proportional to c and D¹ E¹ proportional to a , the angle E¹ O¹ D¹ = θ^1 is a measure of the ratio $a : c$. Thus the Wheatstone bridge condition is satisfied if $\theta = \theta^1$. It will be noticed that as B cos α is very small compared with R the angle θ is always in the neighbourhood of 45°, at all events if the horizontal and vertical scales are to the same scale.

110 There are a very large number of ways of observing the equality of the angles θ and θ^1 of which only a few will be mentioned; e. g. (1) we may place Figure 6 over Figure 5 with O¹ above O and the line O¹ D¹ above O D; then, if the line O¹ H¹ falls on O H, we have equality; (2) the angle θ may be 115 mechanically communicated to one element of

61,5

1,518,477

3

a differential gear, the angle θ^1 to the third element in the opposite sense when a pointer attached to the jockey element will indicate the difference (if any) between θ and θ^1 ; (3) we may arrange the parts as in (1), fix a mirror to O H, say perpendicular, and a second mirror perpendicular to O¹ H¹; then by means such as an auto collimator we may observe the equality or inequality 10 of the angles by known optical means.

A third method of procedure presents many advantages. The Wheatstone bridge equation may be written:

$$15 \quad 1 + \frac{B}{R} \cos \alpha = \frac{a}{c}$$

or

$$\frac{B}{R} \cos \alpha = \frac{a-c}{c}$$

20 Now in Figure 7 let O F be set off to represent R, let F E be set off to represent B cos α , and in Figure 8 let O¹ P represent c and P E¹ represent $a-c$ (obtained by differential gear from a and c); then we may 25 test the equality of the angles E O F and E¹ O¹ P as already described.

Some examples of construction according to this invention will now be described with reference to Figures 9, 10, 11, 12, 13, 14, 15 30 and 16 of the drawings, in which:—

Figure 9 shows a known form of sliding resistance.

Figure 10 shows a method of effecting the adjustment according to the lower part of 35 Figure 4.

Figure 11 is a plan and Figure 12 is a sectional view, the section taken being about the line 21 of Figure 11, showing an arrangement of construction corresponding to 40 Figure 7.

Figure 13 is a plan and Figure 14 is a sectional view, the section taken being about the line 21¹ of Figure 13, showing an arrangement of construction corresponding to 45 Figure 8.

Figure 15 is a plan view and Figure 16 is a side view of the two instruments combined to test the equality or otherwise of the angles O and O¹ shown in Figures 7 and 8.

50 In Figure 9 we have a uniform resistance wire wound as a spiral on an insulating drum. A brush 1 fixed to nut 2 on screw 3 is actuated by handle 4 which may (in certain cases) actuate the measuring apparatus of one of the goniometers; thus the resistance between + and the brush 1 may become a measure of one of the goniometer angles. Suitable gearing is provided between handle 4 and the axis of the drum on which the 55 wire is wound, so that, as 4 is rotated moving brush 1 along screw 3, the drum is also rotated at a suitable rate so that the brush moves continuously along the wire.

In Figure 10 the two arms R and R + B cos α of the Wheatstone bridge circuit Figure 4 are shown together with the slider S. The value of R is communicated to handle 5, to which is fixed wheel 6 gearing with wheels 7 and 8 fixed to drums 9 and 10 respectively. Screw 11 carrying slider S as a 70 nut is also fixed to 5, whose rotation in accordance with R may be produced by an electrical receiver geared thereto or, if 5 is directly operated by hand, suitable means (not shown) for indicating the value of R 75 may be associated with 5. The electrical resistance corresponding to R on the left is represented by the resistance of the wire between brush 12 and slider S. On the right hand side we have to make allowance for the 80 term B cos α which may be + or —.

The value of α is communicated (automatically or otherwise) to screw 16 by means of handle 15 fixed to it. Nut 17 has a brush moving over a series of studs 18 (the middle 85 one at 19 corresponding to the value $\alpha = 90^\circ$); between successive studs are inserted resistance wires corresponding to the values of d (cos α), i. e. of sin α . The figure is drawn for the case when $\alpha = 90^\circ$ in which 90 case R is the resistance between the middle stud at 19 and slider S.

When α is in the position of Figure 1, nut 17 will be upon the upper series of studs (Figure 10) while when α is greater than 95 90° , it will be upon the lower series. Thus if the values of R and α are continuously communicated to the apparatus illustrated in Figure 10 and the values of c and a communicated to the other arms of the Wheatstone bridge, as shown diagrammatically in Figure 4 but not shown in Figure 10, the deflection of the galvanometer to one or the other side will give the pair of quadrants in which the fore-and-aft line of the target 105 lies.

Figures 11 and 12 show an arrangement of construction corresponding to Figure 7. Here 22 is the range receiver geared to screw 23 on which is threaded nut 24 (suitably guided) supporting a flat rod 25 comprising a rack 26 at its distant end. This rack gears with a long pinion rod 30. Carried on the rod 25 is a swivelling pin 27 provided at the upper end with a forked piece 28 in 115 which a flat bar 29 can slide. 29 is pivoted to rock about a fixed pin 31.

The value of α is communicated to shaft 40 carrying arm 41 to which is fixed pin 42, the distance between the centres of 40 and 42 120 representing on the selected scale the base B of Figure 1. In the case of two ships being engaged in the operations, provision must be made for adjusting the radial distance of 42 from 40. Pin 42 engages in a slot 125 43 of a suitably guided frame 44 carrying

a rack 45 engaging with a pinion 46 fixed to 30. As α varies in value, the frame 44 will be moved in its slide, thus rotating pinion rod 30 and translating rack 26 and thereby translating pin 27 and rocking bar 29 about pin 31. A mark 48 at the upper end of 29 indicates by its position the value of the angle at O, Figure 7.

Figures 13 and 14 show an arrangement of construction corresponding to Figure 8. 22¹ represents an electrical receiver giving the value of c . The part 25¹ of Figures 13 and 14 corresponds to and functions as the part 25 of Figures 11 and 12, so 22¹ corresponds to 22 etc. etc., up to 31¹ to 31, and need not be again described.

The value of α is communicated to bevel wheel 71 either by direct gearing, if the apparatus is situated at A, Figure 1, or, 20 if at a distant station, by receiver 70. By means of pinion 73, fixed to screw 23¹, the value of c is communicated to toothed and bevel wheel 72. 74 is the jockey wheel of the differential gear 71, 74, 72. The spindle 25 of 74 is fixed to long pinion rod 30¹, the rotation of which gives a measure of $\alpha - c$, which is communicated to rack 26¹ and pin 27¹ thus angling 29¹ carrying a mark 48¹ about its fulcrum 31¹.

Figures 15 and 16 show the two instruments illustrated in Figures 11 and 12 and Figures 13 and 14 after superposition, that of Figure 11 being placed above that of Figure 13. In Figure 15 it will be seen that pointer 48 is in coincidence with pointer 48¹ corresponding to the broadside-on position. If 48¹ had been to the right or left of 48 one or other of the quadrants X Z or Y W, Figure 17, would have been indicated.

We claim:—

1. Apparatus comprising two goniometers (instruments capable of measuring small angles in a horizontal plane), situated at a distance apart, means associated with one 45 of the goniometers for multiplying the angle determined by that goniometer by the ratio

$\frac{TC}{TP}$

(Figure 1), for the purposes set forth.

2. Apparatus comprising two goniometers situated at a distance apart and means for correlating the two measured angles whereby when (1) the range of the target, (2) the distance between the two goniometers and (3) the angle α , the angle between the line of sight and the base, are known, the sign of the deviation from the broadside on position may be indicated.

3. Apparatus comprising means for determining from each of two positions at a distance apart the horizontal angle subtended at each of these positions by two definite points on a target and a Wheatstone bridge

circuit for multiplying one of the angles determined by the ratio

$\frac{TC}{TP}$

(Figure 1), for the purposes set forth.

4. Apparatus comprising means for determining from each of two positions at a distance apart the horizontal angle subtended at each of these positions by two definite points on a target and a mechanical equivalent of a Wheatstone bridge circuit for multiplying one of the angles determined by the ratio

$\frac{TC}{TP}$

(Figure 1), for the purposes set forth.

5. Apparatus comprising means for determining from each of two positions at a distance apart the horizontal angle subtended at each of these positions by two definite points on a target, a Wheatstone bridge circuit, means for varying the resistance of one of the arms c proportional to the goniometer angle at C (Figure 1), means for varying the resistance in another arm α proportional to the second goniometer angle as measured at A (Figure 1), and means for varying the resistances of the two remaining arms of the bridge to be made proportional (1) to the range R and (2) to the sum of R and B $\cos \alpha$, the resistances c and R being arranged opposite to one another in the circuit.

6. Apparatus comprising two goniometers for determining from each of two positions at a distance apart the horizontal angle subtended at each of these positions by two definite points on a target, a Wheatstone bridge circuit, means for varying the resistance of one of the arms c proportional to the goniometer angle at C (Figure 1), means for varying the resistance in another arm α proportional to the second goniometer angle as measured at A (Figure 1), the resistances of the two remaining arms of the bridge being proportional to 1 and

$$1 + \frac{B \cos \alpha}{R},$$

the resistances c and 1 being arranged opposite to one another in the circuit.

7. Apparatus comprising two goniometers for determining from each of two positions at a distance apart the horizontal angle subtended at each of these positions by two definite points on a target, geometrical means for multiplying one of the goniometer angles determined by the ratio

$\frac{TC}{TP}$

Figure 1, consisting of a first part set out

61.5

1,518,477

5

proportionally to R , a second part set out angularly thereto, preferably perpendicular thereto, and equal to $R + B \cos \alpha$ associated with means for exhibiting the value of θ , 5 that is

$$\tan^{-1} \frac{R + B \cos \alpha}{R},$$

10 means for exhibiting the ratio of $\frac{a}{c}$ and

means for indicating differences between θ and θ^1 , θ^1 being

$$15 \tan^{-1} \frac{a}{c}.$$

8. Apparatus, comprising two goniometers for determining from each of two positions at a distance apart the horizontal angle subtended at each of these positions by two definite points on a target, means capable of being set proportional to R , the range, means capable of being set laterally thereto, preferably perpendicularly thereto, proportional to $B \cos \alpha$, means (Figure 7) for exhibiting the value of 25

$$\tan^{-1} \frac{B \cos \alpha}{R},$$

30 means (Figure 8) for setting out the value of c and for setting out laterally thereto, preferably perpendicularly thereto, the value

of the difference $a - c$ between the two goniometer angles, and means (Figure 8) for exhibiting the value of 35

$$\tan^{-1} \frac{a - c}{c}.$$

9. Apparatus for use in determining the sign of the deviation (whether plus or minus) of the keel line of an enemy ship from the broadside-on position, comprising two goniometers and means for multiplying the goniometer angle observed at one of the stations (say, the station C) by the ratio 40 45

$$\frac{TC}{TP}$$

(Figure 1) so as to give the value of the goniometer angle as measured from an imaginary station P situated at substantially the same distance from the target as the other station A. 50

10. Apparatus according to claim 9 comprising the use of two goniometers at as great a distance apart as possible, associated with means for correlating the two measured angles whereby when (1) the range R , (2) the distance between the two goniometer stations B , and (3) the angle α between the line 55 60 of sight and the base B are known the sign of the said deviation may be indicated.
